his

UNITED STATES PATENT OFFICE.

ARTHUR R. SELDEN, OF ROCHESTER, NEW YORK.

SHOE-TREE.

Application filed October 29, 1920. Serial No. 420,398.

To all whom it may concern:

Be it known that I, ARTHUR R. SELDEN, a citizen of the United States, and resident of Rochester, in the county of Monroe and State of New York, have invented certain new and useful Improvements in Shoe-Trees, of which the following is a specification.

The present invention relates to shoe trees and more particularly to the type provided with a toe piece and a heel piece with a connection for effecting a relative movement between such heel piece and toe piece, and an object of the invention is to provide a novel connection between the heel and the toe piece which will effectively force said pieces in opposite directions, while at the same time it is adjustable to adapt the tree to shoes of different sizes. Still another object of the invention is to improve that type of toe piece which is made from two members or sections adapted to be spread apart in order to expand the toe piece. A still further object of the invention is to construct a shoe tree which will be strong and durable in use and less expensive to manufacture.

To these and other ends, the invention consists of certain parts and combinations of parts all of which will be hereinafter described, the novel features being pointed out in the appended claims.

In the drawings:

Fig. 1 is a plan view of a shoe tree constructed in accordance with this invention;

Fig. 2 is a view of the shoe tree in side elevation showing the heel and toe piece occupying the positions they would occupy when in operative position in a shoe;

Fig. 3 is a fragmentary side elevation showing the shoe tree folded to a position which it will occupy during the insertion into or the removal from a shoe;

Fig. 4 is a plan view of the toe piece expanded to fit the toe of the shoe;

Fig. 5 is a section on the line 5—5, Fig. 1; and

Fig. 6 is a section on the line 6—6, Fig. 2.

Referring more particularly to the drawings, 1 indicates the heel piece and 2 and 3 the two members or sections of the toe piece, the opposed faces of these sections being provided with grooves 4, opening at the rear face of the toe piece and tapering at 5 toward the forward end of the toe piece.

Movement of the sections or members of the toe pieces to spread them apart is, in

this instance, effected by a spreader 6 in the form of a sheet metal plate bent laterally to provide an upstanding flange 7 extending around the front sides and portions of the rear of the spreader, the ends of this flange being bent into parallelism as at 8 and spaced apart for a purpose which will hereinafter appear. The spreader is provided within the flange 7 with two slots 9 which diverge toward the rear of the spreader and through these slots, pins 10 extend, such pins being rigid with the two sections or members 2 and 3 of the toe piece. The inner ends of the slots are restricted at 9' so that when the pins are at the forward ends of the slots, they will be in the restricted portions and prevent loose motion of the toe piece members or sections. With the end in view of limiting the outward swinging movement of the toe piece sections with reference to the spreader so that the forward ends of the toe piece sections will lie in proper relation for insertion in a shoe, the two toe piece sections carry pins 11 which depend from the upper walls of the grooves 4 within the flange 7 cooperating with the inner face of said flange to limit the outward movement of the forward ends of the toe piece sections.

The connecting means between the heel and the toe piece embodies, in this instance, a member 12 immovably secured to the heel piece 1 and having its inner pivoted end curved slightly upwardly. This member 12 is preferably formed from sheet metal bent downwardly along opposite edges to provide a channel, its free end being provided with an upwardly extending lip 13. The other member 14 is bowed from one end to the other and is formed from a strip of sheet metal bent to provide two parallel portions spaced apart and pivoted to the upwardly extending ears 8 on the spreader through a pin 15. The connecting portion 16 between these parallel portions of the member 14 acts as a stop and lies at the free end of the member, being so formed that its opposite edges project beyond the opposite sides of the parallel portions of the member 14 so as to provide means by which the connecting means may be readily operated. The members 12 and 14 of the connecting means are preferably pivoted together by a pivot pin 17 which, in this instance, is in the form of a removable cotter-pin passed through openings in the members

12 and 14. It is preferred to provide the member 12 with a longitudinal series of openings 18 and the member 14 with a plurality of openings 19 through which the 5 cotter-pin may extend, the opening being selected which corresponds to the size of the shoe in which the tree is fitted. For the purpose of indicating this opening, the member 12 is provided on its upper face 10 with a series of numbers 20 or other indicating means.

In using the shoe tree, the connecting means is adjusted to correspond with the size of the shoe. The connecting means is 15 then adjusted in the manner indicated in Fig. 3 and the toe piece is inserted in the toe portion of the shoe. The connecting means is now depressed and this causes the expansion of the toe piece due to the fact 20 that the pins 10 travel in engagement with the walls of the slots 9, while at the same time the forward end of the spreader bears against the forward diverging walls of the grooves 5 and spreads the forward ends of 25 the toe piece sections, thus causing said sections to accommodate themselves to the toe of the shoe. The pivot 17 moves downwardly below the horizontal plane of the connections between the members 12 and 14 30 with the heel and toe pieces, so that the connection automatically locks itself in this position. In some adjustments, the lowermost position of the pivot 17 is determined by the engagement of the member 12 with 35 the pivot pin 15, while with other adjustments the lowermost position of the pivot 17 is determined by the engagement of the connecting portion 16 with the member 12. The removal of the shoe tree is effected by 40 pulling upwardly on the connecting portion 16 which breaks the toggle joint, thereafter permitting the heel and toe pieces to be removed from the shoe.

A shoe tree constructed in accordance with 45 this invention provides a connection between the toe piece sections and a spreader with diverging slots, such connection preventing the swinging of the sections on the pins which operate in the slots. The 50 spreader has upstanding flange portions which not only cooperate with pins on the toe piece sections to prevent the swinging of the toe piece sections, but also cooperate with walls of the grooves in the sections to 55 provide a wide bearing for the spreader. The connecting means between the heel and the toe piece is of novel form, embodying only two parts acting as a toggle, one of said toggle members being preferably rigidly 60 connected to the heel piece, while the other is pivotally connected with the toe piece preferably through a pivotal connection with the spreader. One of these toggle members is, in this instance, formed by two 65 parallel members between which the other

toggle member operates. An adjustable connection is provided between the toggle members so that the tree may be accommodated to shoes of different sizes. The sections or members of the toe piece have two 70 connections with the spreader, one through the walls of the slots and the other which is independent of the first maintains the toe piece members against swinging too far on the first connections. The curved forward 75 end of the spreader by cooperating with the inclined converging walls of the opposed grooves, permits the two sections of the toe piece to rock slightly in order to accommodate the toe piece to the taper of the toe of 80 the shoe.

What I claim as my invention and desire to secure by Letters Patent is:

1. A shoe tree comprising a heel piece, a divided toe piece having the opposed walls 85 of its members provided with grooves, a spreader arranged to operate in said grooves and provided with diverging slots and a marginal flange, pins carried by said members and operating in the slots, pins carried 90 by said members and cooperating with the marginal flange to hold the members in proper operating relation to the spreader, and means connecting the heel piece and the spreader for effecting a movement between 95 said parts.

2. A shoe tree comprising a heel piece, a divided toe piece having the opposed sides of its members provided with grooves, the forward ends of which converge toward each 100 other, a spreader arranged to operate in said grooves and to cooperate with said converging walls to force the members of the toe piece apart and having a curved forward end, said spreader being provided with diverging slots, pins carried by the toe piece members and operating in said slots and permitting the toe piece members to rock on the curved forward end of the spreader, and connecting means between the heel piece 105 and the spreader for effecting the movement between such heel piece and the spreader.

3. A shoe tree comprising a heel piece, a divided toe piece having the opposed sides of its members provided with grooves, the 110 forward ends of which converge toward each other, a spreader arranged to operate in said grooves and provided with diverging slots, the forward ends of which are restricted, the end of the spreader cooperating with the 115 converging end walls of the grooves to spread the sections of the toe piece apart, pins carried by the toe piece sections or members and operating in said slots being received in the restricted portions to lock the 120 toe piece members against free movement when the spreader is moved toward its rear-most position, and connecting means between the heel piece and said spreader for effecting the movement between said parts. 125

4. A shoe tree comprising a heel piece, a divided toe piece having the opposed walls of its members provided with grooves, the forward ends of which converge toward each other, a spreader operating in such grooves and having a curved forward end co-operating with the converging walls, means connecting the spreader with the members of the toe piece, said means permitting the toe piece to rock on the curved forward end 10 of the spreader, and connecting means between such heel piece and the spreader for effecting a movement between the heel piece and the spreader.

ARTHUR R. SELDEN.
